(57) **CLAIM**

The ornamental design for a heat dissipation module as shown and described.

DESCRIPTION

FIG. 1 is a front perspective view of a heat dissipation module showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The evenly-dashed broken lines illustrate portions of the heat dissipation module that form no part of the claimed design. The oblique line shading shown in FIG. 1 and FIG. 3 indicates a transparent or translucent surface.
